United States Patent Office

Des. 212,546
Patented Oct. 29, 1968

212,546

MUG OR SIMILAR ARTICLE

Owen Warren, 5524 E. Belknap
Fort Worth, Tex. 76100

Filed June 19, 1967, Ser. No. 7,516

Term of patent 14 years

(Cl. D44—9)

FIG. 1 is a perspective view of a mug or similar article showing my new design;

FIG. 2 is a side elevation of the same; and

FIG. 3 is a top plan view of the same.

I claim:

The ornamental design for a mug or similar article, as shown.
